COMBINED DRINKING STRAW AND HORN

Ardashus A. Aykanian, Wilbraham, Mass., assignor to
The Coca-Cola Company, Atlanta, Ga.

Filed Jan. 15, 1973, Ser. No. 323,588

Term of patent 14 years

Int. Cl. D7—06

U.S. Cl. D7—42

FIG. 1

FIG. 2

FIG. 3

FIG. 4

FIG. 5

FIG. 6

FIG. 7

FIG. 8

FIG. 1 is a perspective view of a combined drinking straw and horn embodying my new design, wherein the drinking tip has a flattened and rounded end portion.

FIG. 2 is a top plan view of the combined drinking straw and horn illustrated in FIG. 1.

FIG. 3 is a side elevational view of the combined drinking straw and horn illustrated in FIG. 1.

FIG. 4 is an end view of the combined drinking straw and horn illustrated in FIG. 3 and taken from the drinking straw side elevational view.

FIG. 5 is a perspective view of the combined drinking straw and horn, wherein the drinking tip end portion is flattened.

FIG. 6 is a top plan view of the combined drinking straw and horn illustrated in FIG. 5.

FIG. 7 is a side elevational view of the combined drinking straw and horn illustrated in FIG. 5.

FIG. 8 is an end view of the combined drinking straw and horn taken from the right-hand end of the side elevational view illustrated in FIG. 7.

The characteristic feature of my design resides in the combination on the combined drinking straw and horn of a tubular member having an open mouthpiece end and an open opposite end, wherein the mouthpiece end is flattened, bifurcated through its center to form a pair of integral, spaced end portions in plan view and which end portions define a substantially elliptical cross-sectional gap at the mouthpiece end.

I claim:

The ornamental design for a combined drinking straw and horn, as shown and described.
